US0D1075830S

(12) **United States Design Patent** (10) Patent No.: **US D1,075,830 S**
(45) Date of Patent: ** May 20, 2025

(54) **DISPLAY SCREEN OR PORTION THEREOF WITH GRAPHICAL USER INTERFACE**

(71) Applicants: **HYUNDAI MOTOR COMPANY, Seoul (KR); KIA CORPORATION, Seoul (KR)**

(72) Inventor: **Se-Hoon Oh, Yongin-si (KR)**

(73) Assignees: **Hyundai Motor Company, Seoul (KR); Kia Corporation, Seoul (KR)**

(**) Term: **15 Years**

(21) Appl. No.: **35/521,371**

(22) Filed: **May 28, 2024**

(80) **Hague Agreement Data**

Int. Filing Date: **May 28, 2024**

Int. Reg. No.: **DM/237719**

Int. Reg. Date: **May 28, 2024**

Int. Reg. Pub. Date: **Jun. 21, 2024**

(30) **Foreign Application Priority Data**

Apr. 2, 2024 (KR) 30-2024-0012968

(51) LOC (15) Cl. **14-04**

(52) U.S. Cl.

USPC **D14/486**

(58) **Field of Classification Search**

USPC D14/485-495

(57) **CLAIM**

The ornamental design for a display screen or portion thereof with graphical user interface as shown and described.

DESCRIPTION

1. Front. Reproduction 1 is a front view of a display screen or portion thereof with graphical user interface showing our new design.

The outer broken lines in the figure show a display screen or portion thereof, and form no part of the claimed design; the other broken lines in the figure show portions of the graphical user interface that form no part of the claimed design.

1 Claim, 1 Drawing Sheet
